UNITED STATES PATENT OFFICE.

THOMAS E. SCANTLIN, OF LAFAYETTE, INDIANA.

THERMAL ELECTRIC CUT-OUT.

SPECIFICATION forming part of Letters Patent No. 718,660, dated January 20, 1903

Application filed September 5, 1901. Serial No. 74,411. (No model.)

To all whom it may concern:

Be it known that I, THOMAS E. SCANTLIN, a citizen of the United States, residing at Lafayette, in the county of Tippecanoe and State of Indiana, have invented certain new and useful Improvements in Thermal Electric Cut-Outs; and I do declare the following to be a full, clear, and exact description of the invention, such as will enable others skilled in the art to which it appertains to make and use the same.

This invention relates to a thermal electric cut-out primarily designed for protecting telephone and telegraph instruments and equipments from "sneak" currents of higher potentiality or amperage than such instruments and equipments are designed to withstand, but capable also of being employed effectively as a current-arrester in electric circuits and connections of all kinds where protection from abnormal currents is or may be found necessary or desirable.

The object of the invention is to provide a thermal cut-out which is simple of construction, inexpensive of production, and quick-acting.

With this and other objects in view, which will appear as the nature of the improvements is better understood, the invention consists of certain novel features of construction, combination, and arrangement of parts, as will be hereinafter more fully described, and particularly pointed out in the appended claims.

In the accompanying drawings, Figure 1 is a perspective view of a cut-out embodying my invention. Fig. 2 is a longitudinal section of the same. Figs. 3, 4, 4^a, 5, 6, 7, and 8 are views similar to Fig. 2, showing modified forms of the cut-out; and Fig. 9 is a view showing the application of the invention to its supports.

Referring now more particularly to Figs. 1 and 2 of the drawings, the letters *a* *b* indicate the terminals of the cut-out, and *c* its non-conducting casing or receptacle. The terminal *a* has projecting therefrom a pin *d*, which enters the bore of a tube *e*, carried by the terminal *b*. The outer end of this tube has a threaded stem *f*, which fits within a threaded socket in a non-conducting bushing *g*, occupying the opening in the said ter-

minal *b*, which is of ring form. The pin *d* is connected with the tube *e* by the fusible connection *h*, composed of solder or some other fusible material which will melt at a relatively low degree of heat. The terminals *a* and *b* close the ends of the receptacle *c*, and one or both of them may have an endwise-sliding movement to withdraw the pin and tube from engagement when released by the melting of the said fusible connection. The space or chamber between the pin and tube and the wall of the receptacle contains a filling of subdivided or aggregated resistance material *i*, which preferably consists of carbon, German silver, or some other suitable material of low conductivity and high resistance, said material being of pulverulent, powdered, or granular form in order to secure the best results. This material is in electrical connection with the terminals *a* *b*, and when an abnormal current passes through the cut-out or arrester the resistance material becomes heated, and as the heat therefrom is transmitted to the pin and tube the solder or fusible connection between them is melted, leaving them free to be withdrawn from engagement with each other by an endwise-sliding movement of one or both, as desired. The outer surface of the tube *e* is covered with a layer *j* of waxed paper, silk, or other suitable insulating material for the purpose of decreasing the exposed conducting-surface of said tube to cause the current to pass through the resistance material throughout the length of the receptacle, thereby increasing the resistance and producing a higher degree of heat. This result is also promoted by the use of the non-conducting bushing *g* and utilizing the resistance medium for electrically connecting the two terminals, as shown. In the present instance I have shown the terminal *b* as adapted to be moved to withdraw the pin from engagement with the tube, which is effected by means herein-after described.

In the construction shown in Fig. 3 the terminal *a'* is formed with a cup or socket *a'*, containing a non-conducting bushing or washer *g'*, having a threaded bore for the reception of the outer screw-threaded end *d'* of the pin *d*, while the tube *e'* is fixed to or formed integrally with the terminal *b'*. The

pin and tube are connected as before by the fusible connection h' , and the resistance material i' envelops the same and is confined in the casing c' and electrically connects the terminals a' and b' .

In the construction shown in Fig. 4 the two terminals $a^2 b^2$ are united by the fusible connection h^2 with metallic cups or caps k , which close the ends of the receptacle c^2 and are fixed thereto in any desired manner. The resistance material i^2 contained in said receptacle electrically connects the two terminals $a^2 b^2$ through the metallic caps k . When the resistance material is heated by the passage of an abnormal current, the heat is transmitted to the caps k and thence to the solder, which is melted and releases the terminals from said caps. If desired, however, the caps k may be fixed to or formed integrally with the terminals and releasably connected by fusible material h^3 , such as shellac or solder, to the ends of the receptacle, as shown in Fig. 4^a, so as to be disengaged therefrom with the terminals when the shellac or solder is melted.

In the construction shown in Fig. 5 the two caps k' are united by the fusible connection h^4 and are fixed to the inner ends of the sections $c^3 c^4$ of a two-part casing or socket, each section containing a filling of resistance material i^3 , and the outer ends of said sections are formed with threaded sockets m for the reception of screw-threaded stems n on the terminals $a^3 b^3$. By this construction the terminals are electrically connected by the resistance material, caps, and threaded stems, as will be readily understood. The heating of the resistance material and caps causes the fusible connection h^4 to melt and release the two parts of the cut-out from engagement in an obvious manner.

In the construction shown in Fig. 6 the caps k^2 are fixed to the ends of the receptacle, as in Fig. 4, and have conical sockets o , which project into said receptacle and receive conical projections p on the terminals $a^4 b^4$, the said conical sockets and projections being united by the fusible connection h^5 . The electrical connection between the two terminals is here made through the resistance material and the conical members. The operation of the device as thus constructed will be readily understood from the foregoing description.

In the construction shown in Fig. 7 both the pin d^5 and the tube e^5 are insulated from the terminals $a^5 b^5$. The pin d^5 is provided with a screw-threaded end d^6 , which screws into the non-conducting bushing g^5 , which in turn is threaded into the terminal a^5 . The tube e^5 is similarly provided with a threaded stem e^6 , which fits within a threaded socket in the non-conducting bushing e^7 , which is screw-threaded into the end of the terminal b^5 . The pin d^5 fits within the tube e^5 , as in the construction shown in Fig. 2, and is held in place by solder or other fusible material.

The space between the tube e^5 and the non-conducting receptacle or casing c^5 is filled with the resistance material or substance i^5 . 70

In the construction shown in Fig. 8 I do away with the receptacle or casing and unite the two terminals $a^6 b^6$ by an admixture of the subdivided or aggregated substance or material i^6 , which is a conductor, with some 75 suitable material—such as shellac, rosin, glue, or wax—which will bind the parts of the subdivided material together and unite the terminals $a^6 b^6$. Upon the passage of an abnormal current through the terminals this 80 admixture will fuse or melt, and the terminals will thereupon separate, as will be readily understood.

Fig. 9 of the drawings shows one mode of mounting the cut-out and withdrawing the 85 terminals for engagement upon the melting of the fusible connection, the withdrawal of one or both terminals from their normal position being deemed preferable to arrest the passage of any current, although the parts 90 may be so disposed or constructed as to effect the positive cut-off of the current in any other desired way. In Fig. 9 two conducting and supporting plates $q q'$ are mounted upon a suitable base R and are designed to be connected up in the telephone or telegraph or other circuit in any approved manner. Each of these plates is slotted or formed with an open bearing at its upper end, as shown at s , to receive the coöperating terminal a or b , 100 which is grooved at s' to receive the walls of said slot, whereby the cut-out, which extends longitudinally between the plates, is held from endwise movement. A spring detent t is also formed on each plate to bear upon the 105 terminal and hold the same securely seated in the slot. The free end of the plate q , which is of spring metal, is bent out of its normal position to engage the terminal b and is held under spring tension, so that when the fusible connection h is melted said spring by its 110 retractile force will pull the terminal b outwardly, thereby withdrawing the terminals from engagement with each other. Either one or both of the terminals may be mounted 115 in this or any equivalent manner, as desired, and the movable spring-plates upon resuming their normal position may be made to contact with a ground connection, thus throwing the current to the earth until the parts are 120 again restored for operation.

It will be seen from the foregoing description that each embodiment of the invention herein disclosed consists of terminals separable by the action of heat and a resistance medium consisting of a subdivided material formed of aggregated parts, which on becoming heated effects the disconnection of the terminals, thereby cutting off the flow of the current. The specific kind or character of 130 the subdivided material employed is immaterial so long as it is of sufficiently low conductivity to perform this function.

The resistance material may be made of

- any desired subdivided substance or substances of low conductivity and high resistance. The use of carbon or German silver in granular form is preferred; but I have also secured good results from the use of a good conducting material in granular form admixed with a non-conducting material—such as shellac, rosin, glue, cement, or wax—so that the former shall be wholly or partially enveloped in the latter, the current passing from one grain or particle to another and arcing through the non-conducting envelop, thus exciting energy and increasing the resistance and production of heat.
- 15 It is to be understood that by the use of the terms "subdivided resistance," "granular resistance," "resistance medium of aggregated parts," &c., I mean any resistance medium composed of combined parts or particles either loosely confined or bound together by a suitable cement and through which an electric current may pass by a step-by-step movement, as by jumping from one part or particle to another.
- 25 As an instance, as heretofore stated, I may use carbon or German silver in granular or powdered form or any other material of like low conductivity and high resistance. I disclaim the use of aggregated coils of resistance-wire, as a multiple conductor formed of two or more coils would lessen the resistance to an objectionable degree and also materially increase the cost of construction.
- The invention may be employed in electrical equipment of all kinds where the use of a current-arrester is required.
- 35 Having thus described my invention, what I claim as new, and desire to secure by Letters Patent, is—
- 40 1. An electric-current cut-out consisting of two separable bodies, an easily-fusible cement uniting the same, and a resistance medium of aggregated parts adapted to be heated by an abnormal current to fuse said cement and forming a broken or interrupted electrical connection of low conductivity between said bodies through which a current passes by jumping from part to part, substantially as described.
- 45 2. An electric cut-out having terminals

separable by the action of heat, and a resistance medium of aggregated parts adapted to be heated by an abnormal current to effect the separation, substantially as specified.

3. An electric-current cut-out consisting of 55 an envelop having terminals separable by the action of heat and containing a loose granular resistance medium adapted to be heated by an abnormal current to effect the separation, substantially in the manner specified. 6c

4. An electric-current cut-out consisting of a receptacle, terminals, a fusible connection between the terminals, and a granular filler of resistance material within said receptacle to fuse said connection, substantially as set 65 forth.

5. An electric-current cut-out consisting of a receptacle, terminals closing the ends of the receptacle, a fusible connection between the terminals, and a granular filler of a resistance 70 material confined by the terminals within said receptacle and adapted to fuse said connection, substantially as described.

6. An electric-current cut-out consisting of a non-conducting casing, two separable bodies, 75 an easily-fusible cement uniting the separable bodies, and a filler of granular resistance material within the casing for fusing the cement to separate said bodies, substantially 80 as set forth.

7. An electric-current cut-out consisting of a non-conducting casing, terminals closing the ends of the casing, a two-part separable connection between the terminals, one of said parts being insulated from its terminal, an 85 easily-fusible cement uniting the parts of the separable connection, and a filler of a resistance material of aggregated parts within the casing, said filler connecting the terminals and being insulated from one of the said parts 90 of the separable connection, substantially as specified.

In testimony whereof I have hereunto set my hand in presence of two subscribing witnesses.

THOMAS E. SCANTLIN.
